CLAIM

I claim the ornamental design for an American football cap, as shown and described.

DESCRIPTION

FIG. 1 is a perspective view for a football cap showing our new design thereof;

FIG. 2 is a top elevational view thereof;

FIG. 3 is a left side elevational view thereof;

FIG. 4 is a right side elevational view thereof;

FIG. 5 is a front view thereof; and,

FIG. 6 is a rear view thereof.

The broken line showing a football helmet and other design on the football cap is for illustrative purposes only and forms no part of the claimed design.
